Primary Examiner — Cynthia Ramirez*Assistant Examiner* — Xavier Marti-Santos(74) *Attorney, Agent, or Firm* — Raven Patents, LLC;
Anton E. Skaugset(57) **CLAIM**

The ornamental design for a sofa, as shown and described.

DESCRIPTION

FIG. 1 is a front perspective view showing the new design;
 FIG. 2 is a rear perspective view thereof;
 FIG. 3 is a front and left side perspective view thereof;
 FIG. 4 is a rear and right side perspective view thereof;
 FIG. 5 is a left side perspective view thereof; the right side perspective view is a mirror image of this view and has therefore been omitted;
 FIG. 6 is a top perspective view thereof; and,
 FIG. 7 is a bottom perspective view thereof.

1 Claim, 6 Drawing Sheets(56)
